DESIGN FOR AN EMBLEMATIC POSTER

Percy Merton, Hillsdale, N. J.

Application September 26, 1942, Serial No. 108,341

Term of patent 7 years

To all whom it may concern:

Be it known that I, Percy Merton, a citizen of the United States and a resident of Hillsdale, in the county of Bergen and State of New Jersey, have invented the new, original, and ornamental Design for an Emblematic Poster, of which the following is a specification, reference being had to the accompanying drawing forming part thereof, in which—

Fig. 1 is a front face view of the emblematic poster showing my new design.

Fig. 2 is an edge view.

I claim:

The ornamental design for an emblematic poster, substantially as shown.

PERCY MERTON.
